UNITED STATES PATENT OFFICE.

VICTOR BLASEZYK, OF NEW ROME, WISCONSIN.

ENGINE REPAIR STAND.

Application filed December 18, 1922. Serial No. 607,593.

To all whom it may concern:

Be it known that I, VICTOR BLASEZYK, a citizen of the United States, residing at New Rome, in the county of Adams and State of Wisconsin, have invented certain new and useful Improvements in Engine Repair Stands, of which the following is a specification.

This invention relates to a support or stand to hold parts of machines while being repaired, or otherwise operated on, and has for one of its objects to simplify the construction and increase the efficiency and utility of devices of this character.

Another object of the invention is to provide a device of this character which may be readily adjusted to fit parts of machines of various forms and sizes, and wherein means are provided for securely holding the parts in position against strains incident to the repair operation, or the like.

Another object of the invention is to provide a device of this character including a rotatable mandrel or shaft adapted to apply rotary motion to a crank or other shaft to regrind bearings, or to "burn in" bearings or for like purposes, and holding the article being acted on firmly in position.

With these and other objects in view, the invention consists in certain novel features of construction as hereinafter shown and described and then specifically pointed out in the claims, and in the drawings illustrative of the preferred embodiment of the invention—

Figure 1 is a perspective view of the improved apparatus arranged for operation on the crank shaft of an internal combustion motor.

Fig. 2 is a perspective view showing the improved apparatus arranged to support the rear axle of an internal combustion motor.

Fig. 3 is an end elevation of the improved apparatus.

Fig. 4 is a plan view of the improved apparatus.

Figs. 5 and 6 are enlarged details of two of the supporting attachments.

Fig. 7 is an enlarged detail illustrating the engine bed holding means.

Fig. 8 is an enlarged detail of a modified form of holding vise.

The improved apparatus comprises a supporting stand including upper horizontal

rail members 10 extending in parallel relation and leg or standard members 11 of any suitable construction.

Mounted on the rail member 10 at one end are standards 12 and 13 in spaced relation and having bearings 14 and 15 for supporting a shaft or mandrel 16.

The mandrel carries a band wheel 17 which is also the outer member of a friction clutch, the opposing inner clutch device being indicated conventionally at 18 and including an operating lever 19. By this means the motion of the mandrel is controlled.

Attached to or integral with the mandrel 16 is a head or face member 20 having spaced pins 21 extending therefrom as shown.

Connected at the ends to two of the leg members are spaced guide rods 22, and slideable on these rods are a plurality of bars 23 or head members 23 through which a threaded rod 24, extends, the latter having a crank arm 25 at the lower end.

At one end one of the members 23 is provided with an extension 26 swingingly coupled to one of the members 23 as shown at 26' and adapted to be turned vertically, as shown in Figure 7, to form a stop to bear against the bottom of an engine bed when the latter is turned on its side, to assist in holding the bed in position while operating on the cylinders and valve seats.

The members 10 constitute base rails to support the work being operated on, for instance the cylinder body 27 of an internal combustion motor, the rod 24 being utilized to support the cylinder body in position with its crank shaft 28.

The supporting members 23 are preferably provided with a plurality of threaded apertures for the rod 24 as indicated in Fig. 4, to enable the rod to be adjusted for different forms of engine beds.

The supporting rails 10 extend beyond the "tail" standard or leg member 11, and attached as by bolts 29 to the under faces of the extended portions of the rails is a base member 30, the latter extending at its ends beyond the side edges of the rails, as shown. Rising from the member 30 at one end are spaced standards 31 having angular recesses 32 in their upper ends to form rests for a body to be operated on, for instance the

axle casing 33 of the rear axle of an internal combustion motor.

The spaced pins 21 are designed to engage the terminal of the crank shaft 28, and thus form a coupling between the crank shaft and the mandrel 16, so that the rotation of the mandrel will transmit its motion to the crank shaft.

At its opposite ends the base member 30 is provided with a socket 34 to interchangeably receive various forms of standards carrying various forms of supports: For instance one standard, represented at 35 in Fig. 5, is provided with a block or transverse head 36 having a longitudinally directed bore to receive a rod 37 threaded at one end to receive a wing nut 38, the block having an upwardly opening slot indicated at 39 and the rod having an upturned end 40 extending through the slot end for some distance above the upper face of the block, and the block also provided with a stationary pin 41 near the unslotted end.

The member 30 is provided with means such as a set screw 42 operating against the standard 35 when in the socket 34, to hold the standard in position vertically.

The block or head 36 is designed to support a bearing cap in reversed position while being operated on, the pins 40 and 41 entering the bolt apertures of the cap and holding it from lateral displacement. By arranging the pin 40 for adjustment longitudinally of the block, by actuating the wing nut 38, the device may be adapted to caps of different sizes, or strain applied to hold the cap in position.

By this means the cap is firmly held while being operated on, as will be obvious.

Another standard 43 is likewise provided and having a transverse head 44 provided with apertures in the ends to receive portions of machines to be operated on, for instance a valve stem 46 as shown in Fig. 6, each end being provided with a set screw 47 to enable the article being operated on to be firmly held.

In Fig. 8 another form of holding vise is shown comprising a standard 70 to engage in the aperture 34 and having a transverse head 71 from which spaced clamp bolts 72 rise and operate through a clamping member 73, springs 74 being disposed around the bolts between the members 71 and 73 and clamp nuts 75 engaging the bolts 72 externally of the members 37. By this simple means standard 70 may be supported by the set screw 42 in the member 30 and an object to be worked on supported between the members 71 and 73.

Attached at one end at 48 to the member 30 is a flexible member, for instance a chain 49 having a loop nut 50 at the outer end.

A rod 51 threaded at one end to engage the nut 50, extends through the member 30 and

is formed with a turn handle at the other end and with an intermediate stop 53 to bear against the lower face of the member 30.

After the work, for instance the axle casing 33, is disposed within the recesses 32 of the standards 31, the chain 49 is passed around the casing and the bolt 51 passed up through the member 30 and engaged with the nut 50, and strain applied by rotating the rod by its handle 52, the stop 53 holding the rod from longitudinal movement, as will be obvious.

One of the standards 35 will preferably be inserted in the socket 34 in the member 30 and adjusted with its block 36 beneath the casing 33, and coacting with the standard 31 to support the casing.

By this means the work will be firmly held in position to enable it to be assembled or disassembled, or otherwise treated.

In Fig. 3 at the right, a simply constructed vise device is shown adapted to support the piston 54 and connecting rod 55 of an internal combustion motor, consisting of a stock 56 to engage in the socket 34, and provided with a transverse head 57 having upstanding standards 58.

The standards 58 are provided with transverse threaded apertures to receive clamp screws 59 to bear within the pin openings of the piston, and thus hold the latter in position between the standards.

Set screws, one of which is shown at 60, are tapped through the head 57, to bear beneath the piston 54 and prevent the latter from tilting on the holding screws 59.

Attached to the transverse lower members of the leg portions 11 is a tubular guide and support 61, and telescopically engaging in the guide is a stay member 62 preferably tubular, and rising from the stay member at its free end is a tubular standard 63, and slidably engaging in the standard is an extension member 64 adjustably supported in position relative to the member 63, by a set screw 65.

At the juncture of the members 62 and 63 the lateral extensions 66 are connected as shown in Fig. 3 to form supporting feet, and at its upper end the extension member 64 is formed with a lateral head 67 to provide a support for the work held on the standards 31-32, for instance the casing 68 of the main drive shaft and the braces 69 of a motor driven vehicle, while the axle casing 33 is being held in position as above described.

The parts 61-62-63-64-66 and 67 will preferably be of gas or steam piping, as shown, and coact with the standards 31 to form an effectual means for supporting the axle casing and its main shaft casing and brace parts, as before stated.

By this simple arrangement a complete, compact and convenient device is produced.

whereby the different parts of a machine can be effectually held in position while being operated on and in convenient relative position so that it is not necessary to move 5 from one part of the shop to the other, or carry the articles to be treated from one place to another.

For instance Fig. 1 illustrates the manner of holding an engine casing in position 10 while the crank bearings are being "burned in," or otherwise treated. Fig. 2 illustrates the manner of holding the rear axle casing and its associated parts in position. Fig. 3 likewise illustrates the manner of holding 15 the piston head and the connecting rod in position while being acted upon.

The improved device is simple in construction, can be inexpensively manufactured of any suitable material and of any 20 suitable size, and operates effectually for the purposes described.

The preferred embodiment of the invention is disclosed in the drawings and set forth in the specification, but it will be 25 understood that modifications within the scope of the claims may be made in the construction without departing from the principle of the invention or sacrificing any of its advantages.

Having thus described the invention what 30 is claimed as new is:

1. In an apparatus of the class described a support, rail members in spaced parallel relation carried by said support, guide rods in 35 parallel relation to the rail members, a bar slidable on the rods, a stop element swingingly coupled to said bar at one end, means for limiting the movement of said stop element in one direction, and clamping means 40 operating through said bar and adapted to engage the body to be operated on to hold it in position on the rails.

2. In an apparatus of the class described a support, including a mandrel and mounted 45 for rotation, a head member carried by said mandrel and adapted to be coupled to the

device to be rotated, rail members in spaced parallel relation carried by said support, guide rods in parallel relation to the rail member, a bar slidable on the rods, a stop element swingingly coupled to said bar at one end, means for limiting the movement of 50 said stop element in one direction, clamping means operating through said bar and adapted to engage the body to be operated on to hold it in position on the rails, a transverse member attached beneath said rails, spaced standards rising from said transverse member and having recesses in their upper faces, a flexible member connected at one end 55 to said transverse member and attached to a nut at the other end, and a threaded rod extending through said transverse member and engaging said nut, whereby an article engaging in the recesses of said standards may 60 be held in position thereon.

3. In an apparatus of the class described a support including a mandrel mounted for rotation therein, longitudinally directed rail members, a head member carried by said 70 mandrel and adapted to be coupled to the device to be rotated, guide rods in parallel relation to the rail members, a bar slidable on said rods, a stop element swingingly coupled to said bar at one end, means for limiting the movement of said stop element in one 75 direction, and clamping means operative through said bar and adapted to engage the body to be operated on to hold it in position on the rails.

4. In an apparatus of the class described a support, rail members in spaced parallel relation carried by said support, guide rods in parallel relation to the rail members, a bar slidable on the rods, and clamping means 85 operating through said bar and adapted to engage the body to be operated on to hold it in position on the rails.

In testimony whereof, I affix my signature hereto.

VICTOR BLASEZYK.
